DESIGN FOR A FOUNTAIN TOOTHBRUSH

Hyman W. Bergman, Kansas City, Mo., assignor
of one-fourth to Theodore A. Landy and one-
fourth to Norman Yarmo, both of Kansas City,
Mo.

Application October 21, 1940, Serial No. 95,962

Term of patent 14 years

To all whom it may concern:

Be it known that I, Hyman W. Bergman, a citizen of the United States, residing at 4931 State Line, Kansas City, in the county of Jackson and State of Missouri, have invented a new, original, and ornamental Design for a Fountain Toothbrush, of which the following is a specification, reference being had to the accompanying drawing, forming part thereof.

In the drawing:

Fig. 1 is a perspective view of the fountain toothbrush showing my new design.

Fig. 2 is a bottom view of the fountain toothbrush shown in Fig. 1.

Fig. 3 is a side elevation thereof.

Fig. 4 is a side elevation with plunger partially withdrawn.

Fig. 5 is an end elevation of the handle of the fountain toothbrush.

Fig. 6 is an elevation of the bristle end of the fountain toothbrush.

I claim:

The ornamental design for a fountain toothbrush, as shown.

HYMAN W. BERGMAN.
